UNITED STATES PATENT OFFICE.

BERT W. DANFORD, OF LANSING, AND ERROL E. EMSHILLER, OF EAST LANSING, MICHIGAN.

VALVE STRUCTURE.

Application filed November 28, 1923. Serial No. 677,476.

To all whom it may concern:

Be it known that we, BERT W. DANFORD and ERROL E. EMSHILLER, citizens of the United States, residing, respectively, at Lansing, county of Ingham, State of Michigan, and East Lansing, county of Ingham, State of Michigan, have invented certain new and useful Improvements in Valve Structures, of which the following is a specification, reference being had therein to the accompanying drawing.

This invention comprises a valve structure. It is especially applicable for use in connection with an internal combustion engine, and it is contemplated to provide mechanism which will insure proper intake of combustible mixture and proper exhaust of the gases after the mixture has been fired in the cylinders. Another object is the elimination of springs, chain-and-sprocket, bevel or worm gear connections, and unnecessary valve-members, which will simplify the method of operation, make the parts more accessible, and minimize vibration.

A still further object of the invention is to provide a valve-structure wherein the valve-members are rotated around a common axis, one upon another, each being provided with intake and exhaust openings and arranged in connected sections so that any section may be easily removed and replaced, the entire structure being mounted in a valve-seat provided in the cylinder-block in proximity to the cylinders. This arrangement minimizes the liability of the valves becoming carbonized, and assures more even and positive action in addition to smoothness of operation.

Other objects and advantages of the invention will in part be apparent and in part be brought out more fully in the description which follows:

An embodiment of the invention is illustrated in the accompanying drawings, the following views being shown:

Figure 1 is a view in top-plan, and partly in section, showing the cylinder-block of an internal combustion engine and illustrating one embodiment of the invention associated therewith;

Fig. 2 is a view in front elevation, showing an arrangement of gearing for driving the valve-mechanism;

Fig. 2^a is a view in side-elevation of the gearing shown in Fig. 2;

Fig. 3 is a view in top-plan, and partly in section, of an outer valve-member, showing the arrangement of intake and exhaust openings therein;

Fig. 4 is a similar view of the inner valve-member removed from within the outer-member, but in the position it would assume with relation thereto if assembled;

Figs. 5 and 6 are detail fragmentary sectional views showing a manner of connecting sections of the outer and inner members, respectively, and their structure at the point of connection;

Figs. 7, 8, 9 and 10 are detail views in section through the valve-members in assembled position, the intake and exhaust ports being in the positions shown in Figs. 3 and 4, respectively, and illustrating the positions of the valve-members of the different cylinders at a given position of the crank-shaft.

In these views, the reference-character 1 designates the cylinder-block of an internal combustion engine. It is provided with the usual cylinders and with intake-openings 2 and exhaust-openings 3 set into the side of the cylinder-block. These are in communication with the cylinders through channels 4, indicated in Figs. 7 to 10, and intersecting these channels is an elongated cylindrical opening or valve-seat in which is disposed valve-mechanism for controlling the passage of fuel to each cylinder and the exhaust of combusted gases therefrom.

As here shown, the valve-mechanism includes an outer valve-member 5, which may be made in sections secured together, generally one section for each cylinder; one method of connecting the sections being shown in Fig. 5. Here the sections are secured by threaded connections 6. The innermost section is closed at the end either by the portion of the cylinder against which it abuts or by a wall 7, as here shown, or other suitable means. A central opening or channel extends the length of the member to constitute a hollow cylinder mounted for rotation in the cylindrical opening in the cylinder-block, the opening constituting a valve-seat for the outer-member. The individual sections are alternately provided with intake-openings 8 and exhaust-openings 9 in alternating pairs arranged along the length

of the member, the openings being placed so as to be in approximate alignment with the openings 2 and 3 in the cylinder-block, and adapted to be successively brought into register therewith.

The inner-member is likewise composed of sections 10 secured together suitably as by threaded connections 11, but each individual section being separated by a wall or plug 12, as best seen in Fig. 6. The sections are arranged end-to-end, and are of cylindrical shape adapted to set within and be rotated with relation to the outer-member. The outer ends of the innermost and outermost sections are closed and either two sets of intake openings 13 or two sets of exhaust openings 14 are provided in each section, except the end sections which have either just one set of intake openings or one set of exhaust openings each. There are two openings to a set here shown, one in advance of another about 90 degrees apart on the periphery.

Arrangement is made for rotating the inner and outer valve-members so that the ports of each section will be brought into register with the intake and exhaust ports in the cylinder-block, successively, and for this purpose the outer-member has a section 15 provided with a portion extended out beyond the plane of the surface of the cylinder-block and upon this is mounted a gear 16. The inner-member has a portion of a section extended outwardly beyond the end 25 of the outer-member and this also carries a gear 17. These gears are in mesh with intermediate gears 18 and 19, mounted for rotation on a stub-shaft extending outwardly from the cylinder-block and driven by a pinion 19 mounted on and keyed to the crank-shaft. The gearing is of a ratio such that the inner valve-member will be driven at a speed the same as that of the crank-shaft, while the outer-member will be driven at a speed one-half that of the crank-shaft. The intake and exhaust ports are so arranged that rotation of the members in this ratio will bring the intake-openings in the inner and outer members into alignment with each other and with an intake-opening in the cylinder-block once in two revolutions of the crank-shaft. The same is true of the outlet openings, these being placed to register at a proper time after the registering of the intake-openings, so that there may be a compression and firing of the combustible gases within the cylinder. In other words, the inner-member is driven at the same angular velocity as the crank-shaft and the outer-member at one-half the angular velocity of the crank-shaft in a four-cycle arrangement. The gearing as shown constitutes a positive drive for the members, avoiding the liability of wear, vibration and lost motion in chain- and sprocket and bevel-gear assemblies.

In Figs. 7 to 10, positions of the openings in the inner and outer valve-members are shown which would correspond with a four-cylinder assembly. In Fig. 7, the intake and exhaust openings are shown in a position corresponding to that of the openings at the right of Figs. 3 and 4, but with the members in assembled position, that is, Figs. 7, 8, 9 and 10 (in the order given) represent the valve sections from right to left as shown in Figs. 3 and 4, respectively. The cylinder 1 is shown with the intake-openings in register with each other and with the intake-opening in the cylinder-block. The exhaust-ports are closed, or out of register with each other, and the positions of the intake and exhaust openings of the other cylinders at a given position of the crank-shaft are indicated in the different figures. The crank-shaft position selected corresponds with the intake position of the first cylinder.

The invention provides a simple, easily accessible valve arrangement wherein there is a positive drive of the members, and while it has been illustrated in connection with the embodiment herein shown, it will be understood that we do not wish to be limited to the precise form of this disclosure, as many changes in the construction and arrangement of the parts are thought to be within the scope of the invention as set forth in the claims.

What we claim is:

1. A valve-structure comprising an inner-member including sections connected together and provided with intake and exhaust openings arranged adjacent and longitudinally of the valve and adapted to be brought into register with intake and exhaust openings of an engine cylinder; an outer valve-member including sections connected together and also provided with intake and exhaust openings arranged adjacent and longitudinally of the valve and adapted to be brought into register with corresponding openings in the inner-member; and means, including a train of gears connected with a driven part of the engine, for positively rotating the members in the same direction to bring the openings therein into register.

2. A valve-structure comprising an inner-member including sections connected together and provided with intake and exhaust openings arranged adjacent and longitudinally of the valve and adapted to be brought into register with intake and exhaust openings of an engine cylinder; an outer valve-member including sections connected together and also provided with intake and exhaust openings arranged adjacent and longitudinally of the valve and adapted to be brought into register with corresponding openings in the inner-member; and means, including a train of gears connected with a driven part of the engine, for positively ro-

tating the members in the same direction at fixed relative speeds to bring the openings therein into register; said connections between the members comprising threaded members adapted to be threaded one into another.

3. A valve-structure comprising an inner-member including sections connected together and provided with intake and exhaust openings arranged adjacent and longitudinally of the valve and adapted to be brought into register with intake and exhaust openings of an engine cylinder; an outer valve-member including sections connected together and also provided with intake and exhaust openings arranged adjacent and longitudinally of the valve and adapted to be brought into register with corresponding openings in the inner-member; means, including a train of gears connected with a

driven part of the engine, for positively rotating the members in the same direction at fixed relative speeds to bring the openings therein into register; the outer-member being mounted for rotation in a portion of an engine; the inner-member being mounted for rotation within the outer-member; said outer-member having a portion extending out beyond a surface of the engine cylinder; a gear mounted thereon; the inner-member having a portion extended outwardly beyond the end of the outer-member; a gear mounted thereon; a pinion on a shaft driven from the engine; and intermediate gearing connecting the pinion and the gears on the outer and inner members, respectively. 25
